(57) **ABSTRACT**

To improve print quality, a plurality of heating resistors (14) are arranged with spaces therebetween on a heat storage layer (13) laminated on a surface of a supporting substrate (11) via an adhesive layer (12) made of an elastic material. A cavity portion (19) is formed at a region between the supporting substrate (11) and the heat storage layer (13), the region being opposed to a heat generating portion of each of the plurality of heating resistors (14). The elastic material constituting the adhesive layer (12) is arranged so that the elastic material is in a bonded state with respect to at least a part of a surface of the heat storage layer (13) opposed to the cavity portion (19).

THERMAL HEAD**

RELATED APPLICATIONS

This application claims priority under 35 U.S.C. §119 to Japanese Patent Application No. JP2008-304371 filed on Nov. 28, 2008, the entire content of which is hereby incorporated by reference.

BACKGROUND OF THE INVENTION

1. Field of Invention

The present invention relates to a thermal head and a manufacturing method therefor, and a thermal printer, the thermal head being used in the thermal printer often mounted to a portable information equipment terminal typified by a compact hand-held terminal and being used to perform printing on a thermal recording medium based on printing data with the aid of selective driving of a plurality of heating elements.

2. Description of the Related Art

Recently, the thermal printers have been widely used in the portable information equipment terminals. The portable information equipment terminals are driven by a battery, which leads to strong demands for electric power saving of the thermal printers. Accordingly, there have been growing demands for thermal heads having high heat generating efficiency.

As a thermal head having high heat generating efficiency, one which has a structure disclosed, for example, in Japanese Patent Application Laid-Open No. 2007-83532 is known.

However, in the thermal head disclosed in FIG. 3 of Japanese Patent Application Laid-Open No. 2007-83532, a substrate (supporting substrate) and a heat storage layer are bonded to each other by anode bonding. Therefore, if a monocrystal silicon substrate having the thermal expansion coefficient of 3.3×10^{-6} per degree centigrade is used as the substrate, and if soda glass that is inexpensive and has good workability but has the thermal expansion coefficient of 8.6×10^{-6} per degree centigrade is used for the heat storage layer, a thermal expansion difference occurs between the substrate and the heat storage layer because of the temperature of a heating resistor that rises up to approximately 200 to 300 degrees centigrade when the thermal head is energized. As a result, a warpage or a distortion may occur in the thermal head so that the thermal head cannot contact correctly with thermal recording paper, which may cause a deterioration in print quality.

In contrast, if a monocrystal silicon substrate having the thermal expansion coefficient of 3.3×10^{-6} per degree centigrade is used as the substrate, and if Pyrex glass that is expensive and has bad workability but has the thermal expansion coefficient of 3.2×10^{-6} per degree centigrade is used for the heat storage layer, a warpage or a distortion does not occur in the thermal head. However, there are problems that manufacturing cost increases and that manufacturing steps are complicated.

On the other hand, an amount of heat flowing in the substrate side is restricted merely by using a thin glass plate having low thermal conductivity as the heat storage layer. However, in order to secure mechanical strength of the heat storage layer, it is necessary to set the thickness of the heat storage layer to be larger than 20 μm . As a result, there is also

a problem that sufficient heat cannot be stored in the heat storage layer when the printing is started, and hence print density becomes low.

SUMMARY OF THE INVENTION

The present invention has been made to solve the problems described above, and it is an object thereof to provide a thermal head that can improve print quality.

10 In order to solve the problems described above, the present invention adopts the following means.

In a thermal head according to a first aspect of the present invention, a plurality of heating resistors are arranged with spaces therebetween on a heat storage layer laminated on a 15 surface of a supporting substrate via an adhesive layer made of an elastic material. A cavity portion is formed at a region between the supporting substrate and the heat storage layer, the region being opposed to a heat generating portion of each of the plurality of heating resistors. The elastic material constituting the adhesive layer is arranged so that the elastic 20 material is in a bonded state with respect to at least a part of a surface of the heat storage layer opposed to the cavity portion.

According to the thermal head of the first aspect of the present invention, the another surface of the heat storage layer is covered with the adhesive layer made of a resin so that the adhesive layer reinforces the heat storage layer (mechanical strength of the heat storage layer is increased (improved)). Therefore, the thickness of the heat storage layer can be reduced (to be 20 μm or smaller), and hence a time period for 25 storing sufficient heat in the heat storage layer can be shortened. Thus, it is possible to eliminate a defective condition that the print density is low when the printing is started.

In addition, an amount of heat input into the heat storage 30 layer when the printing is started can be reduced by decreasing the thickness of the heat storage layer. Therefore, a thermal load applied to the entire thermal head can be reduced, and hence durability and reliability can be improved.

Further, the thermal expansion difference that occurs 35 between the supporting substrate and the heat storage layer 40 because of the temperature of the heating resistors that rises up to approximately 200 to 300 degrees centigrade when the thermal head is energized is absorbed by elastic deformation of the adhesive layer made of an elastic material. Therefore, a warpage or a distortion is eliminated (or reduced) when the 45 thermal head is energized, and hence the print quality can be maintained to be always in an optimal condition.

Still further, even if a monocrystal silicon substrate is 50 adopted as a material of the supporting substrate, soda glass that is inexpensive and has good workability can be adopted as a material of the heat storage layer. Therefore, manufacturing cost can be reduced and manufacturing steps can be simplified.

Still further, beneath the region covered with a heat generating portion of each of the plurality of heating resistors 55 (region opposed to the heat generating portion), there is formed a cavity portion having a sufficient height (depth) for improving the heat generating efficiency, that is, a heat insulating layer for restricting heat flowing into the supporting substrate from the heat storage layer. Therefore, the heat generating efficiency can be improved.

In the thermal head according to the first aspect described above, it is more preferred that the cavity portion include a concave portion formed in the surface of the supporting substrate and the adhesive layer for closing an open end of the 60 concave portion.

According to the thermal head described above, the entire of another surface of the heat storage layer is covered with the

adhesive layer made of a resin so that this adhesive layer further reinforces the heat storage layer (mechanical strength of the heat storage layer is further increased (improved)). Therefore, the thickness of the heat storage layer can be further reduced so that the time period for storing sufficient heat in the heat storage layer can be further shortened. Thus, the defective condition that the print density is low when the printing is started can be eliminated.

In the thermal head described above according to the first aspect described above, it is more preferred that the cavity portion include a concave portion formed in a back surface of the adhesive layer and the supporting substrate that closes the concave portion.

According to the thermal head described above, the entire of the another surface of the heat storage layer is covered with the adhesive layer made of a resin so that this adhesive layer further reinforces the heat storage layer (mechanical strength of the heat storage layer is further increased (improved)). Therefore, the thickness of the heat storage layer can be further reduced so that the time period for storing sufficient heat in the heat storage layer can be further shortened. Thus, the defective condition that the print density is low when the printing is started can be eliminated.

In the thermal head described above, it is more preferred that a part of the back surface of the heat storage layer opposed to the surface of the supporting substrate exposed to the cavity portion be exposed to the cavity portion.

According to the thermal head described above, a part of the another surface of the heat storage layer positioned beneath the region covered with a heat generating portion of each of the plurality of heating resistors (region opposed to the heat generating portion) is exposed to the cavity portion. Therefore, heat dissipation via the adhesive layer is further suppressed so that the heat generating efficiency can be further improved.

The thermal printer of the present invention is provided with a thermal head having high heat generating efficiency.

According to the thermal printer of the present invention, printing on thermal recording paper can be performed with small electric power, and hence duration time of a battery can be lengthened and reliability of the entire printer can be improved.

A manufacturing method for a thermal head according to a second aspect of the present invention including forming a concave portion in a surface of a supporting substrate; laminating an adhesive layer made of an elastic material on a surface of a heat storage layer; bonding the heat storage layer in a laminated state with respect to the surface of the supporting substrate via the adhesive layer; and forming a plurality of heating resistors with spaces therebetween at a region corresponding to the surface of the heat storage layer, the region being opposed to the concave portion.

A manufacturing method for a thermal head according to a third aspect of the present invention including: laminating an adhesive layer made of an elastic material on a surface of a heat storage layer; forming a concave portion in a surface of the adhesive layer; bonding the heat storage layer in a laminated state with respect to a surface of a supporting substrate via the adhesive layer; and forming a plurality of heating resistors with spaces therebetween at a region corresponding to the surface of the heat storage layer, the region being opposed to the concave portion.

According to the manufacturing method for the thermal head of the second aspect of the present invention or the manufacturing method for the thermal head of the third aspect of the present invention, the another surface of the heat storage layer is covered with the adhesive layer made of a resin so

that the heat storage layer reinforced by the adhesive layer (having increased (improved) mechanical strength) is handled. Therefore, manufacturing steps can be simplified and manufacturing cost can be reduced.

In addition, even if a monocrystal silicon substrate is adopted as a material of the supporting substrate, soda glass that is inexpensive and has good workability can be adopted as a material of the heat storage layer. Therefore, manufacturing cost can be reduced and manufacturing steps can be simplified.

According to the present invention, it is possible to provide the effect of improving the printing quality.

BRIEF DESCRIPTION OF THE DRAWINGS

In the accompanying drawings:

FIG. 1 is a longitudinal sectional view of a thermal printer provided with a thermal head according to the present invention;

FIG. 2 is a plan view of a thermal head according to a first embodiment of the present invention, which illustrates a state of eliminating a protective film;

FIG. 3 is a cross sectional view taken along the arrow α-α in FIG. 2;

FIG. 13 is a process diagram for illustrating a manufacturing method for a thermal head according to the third embodiment of the present invention;

FIG. 14 is a process diagram for illustrating a manufacturing method for a thermal head according to another embodiment of the present invention;

FIG. 15 is a cross sectional view of a thermal head according to a fourth embodiment of the present invention, which is similar to FIG. 3;

FIG. 16 is a cross sectional view of a thermal head according to a fifth embodiment of the present invention, which is similar to FIG. 3;

FIG. 17 is a cross sectional view of a thermal head according to a sixth embodiment of the present invention, which is similar to FIG. 3;

FIG. 18 is a cross sectional view of a thermal head according to a seventh embodiment of the present invention, which is similar to FIG. 3;

FIG. 19 is a process diagram for illustrating a manufacturing method for the thermal head according to the seventh embodiment of the present invention;

FIG. 20 is a process diagram for illustrating a manufacturing method for the thermal head according to the seventh embodiment of the present invention;

FIG. 21 is a process diagram for illustrating a manufacturing method for the thermal head according to the seventh embodiment of the present invention;

FIG. 22 is a process diagram for illustrating a manufacturing method for the thermal head according to the seventh embodiment of the present invention;

FIG. 23 is a process diagram for illustrating a manufacturing method for the thermal head according to the seventh embodiment of the present invention;

FIG. 24 is a process diagram for illustrating a manufacturing method for the thermal head according to the seventh embodiment of the present invention;

FIG. 25 is a process diagram for illustrating a manufacturing method for the thermal head according to the seventh embodiment of the present invention;

FIG. 26 is a cross sectional view of a thermal head according to an eighth embodiment of the present invention, which is similar to FIG. 3;

FIG. 27 is a cross sectional view of a thermal head according to a ninth embodiment of the present invention, which is similar to FIG. 3;

FIG. 28 is a process diagram for illustrating a manufacturing method for the thermal head according to the ninth embodiment of the present invention;

FIG. 29 is a process diagram for illustrating a manufacturing method for a thermal head according to another embodiment of the present invention;

FIG. 30 is a process diagram for illustrating a manufacturing method for the thermal head according to another embodiment of the present invention;

FIG. 31 is a process diagram for illustrating a manufacturing method for a thermal head according to a tenth embodiment of the present invention;

FIG. 32 is a process diagram for illustrating a manufacturing method for a thermal head according to still another embodiment of the present invention;

FIG. 33 is a diagram illustrating a concrete example of patterning an adhesive layer, which is a plan view of the adhesive layer viewed from a heat storage layer side or a substrate side;

FIG. 34 is a diagram illustrating a concrete example of patterning the adhesive layer, which is a plan view of the adhesive layer viewed from the heat storage layer side or the substrate side;

FIG. 35 is a diagram illustrating a concrete example of patterning the adhesive layer, which is a plan view of the adhesive layer viewed from the heat storage layer side or the substrate side;

FIG. 36 is a diagram illustrating a concrete example of patterning the adhesive layer, which is a plan view of the adhesive layer viewed from the heat storage layer side or the substrate side;

FIG. 37 is a diagram illustrating a concrete example of patterning the adhesive layer, which is a plan view of the adhesive layer viewed from the heat storage layer side or the substrate side;

FIG. 38 is a diagram illustrating a concrete example of patterning the adhesive layer, which is a plan view of the adhesive layer viewed from the heat storage layer side or the substrate side;

FIG. 39 is a diagram illustrating a concrete example of patterning the adhesive layer, which is a plan view of the adhesive layer viewed from the heat storage layer side or the substrate side; and

FIG. 40 is a diagram illustrating a concrete example of patterning the adhesive layer, which is a plan view of the adhesive layer viewed from the heat storage layer side or the substrate side.

DETAILED DESCRIPTION OF THE PREFERRED EMBODIMENTS

Hereinafter, description is made of a first embodiment of a thermal head according to the present invention with reference to FIGS. 1 to 10.

FIG. 1 is a longitudinal sectional view of a thermal printer provided with the thermal head of the present invention. FIG. 2 is a plan view of the thermal head according to this embodiment, which illustrates a state of eliminating a protective film. FIG. 3 is a sectional view taken along the arrow α - α of FIG. 2. FIGS. 4 to 10 are process diagrams for illustrating a manufacturing method for the thermal head according to this embodiment.

As illustrated in FIG. 1, a thermal printer 1 includes a main body frame 2, a platen roller 3 horizontally arranged, a thermal head 4 arranged oppositely to an outer peripheral surface of the platen roller 3, a paper feeding mechanism 6 for feeding out thermal recording paper 5 between the platen roller 3 and the thermal head 4, and a pressure mechanism 7 for pressing the thermal head 4 against the thermal recording paper 5 by a predetermined pressing force.

As illustrated in FIG. 2 or 3, the thermal head 4 includes a supporting substrate (hereinafter referred to as a "substrate") 11, an adhesive layer 12 made of an elastic material (or an elastic material layer or a stress relaxation layer) that is formed to cover the entire of the another surface (lower surface in FIG. 3) of a heat storage layer 13, and the heat storage layer 13 that is bonded to the substrate 11 via the adhesive layer 12. In addition, one surface (upper surface in FIG. 3) of the heat storage layer 13 is provided with a plurality of heating resistors 14 that are formed (arranged) with spaces therebetween in one direction. Further, as illustrated in FIG. 3, the thermal head 4 includes a protective film 15 for covering the one surface (upper surface in FIG. 3) of the heating resistor 14 and the heat storage layer 13 so as to protect the same from abrasion and corrosion.

Note that, on another surface (lower surface in FIG. 3) of the substrate 11, there is provided a heat dissipation plate (not shown).

Each of the heating resistors 14 includes a heating resistor layer 16 formed on one surface of the heat storage layer 13 in a predetermined pattern, an individual electrode 17 formed on one surface (upper surface in FIG. 3) of the heating resistor layer 16 in a predetermined pattern, and a common electrode 18 formed on one surface (upper surface in FIG. 3) of the individual electrode 17 in a predetermined pattern.

Note that, an actually heat generating portion of each of the plurality of the heating resistors 14 (hereinafter, referred to as "heat generating portion") is a portion not overlapped with the individual electrode 17 and the common electrode 18.

As illustrated in FIGS. 2 and 3, a concave portion 20 for forming cavity portions (hollow heat insulating layers) 19 is formed on the surface (upper surface in FIG. 3) of the substrate 11.

A concave portion 20 is provided so as to form a cavity portion 19 for each of the heating resistors 14. The concave portion 20 and the concave portion 20 are separated (comparted) by an interdot partition 21 (see FIG. 2). In addition, a plurality of concave portions 20 are formed on the surface of the substrate 11, and hence the entire surface of the interdot partition 21 between the concave portion 20 and the concave portion 20 contacts with the back surface of the heat storage layer 13 via the adhesive layer 12.

Each of the cavity portions 19 is a space formed beneath a region covered with the heat generating portion of each of the plurality of the heating resistors 14 (region opposed to the heat generating portion), that is, a space formed (enclosed) by the another surface (lower surface in FIG. 3) of the adhesive layer 12, wall surfaces forming the concave portion 20 (surfaces orthogonal to the one surface of the substrate 11 and the another surface of the heat storage layer 13), and bottom surface (surface horizontal to the one surface of the substrate 11 and the another surface of the heat storage layer 13). Further, a space layer in each of the cavity portions 19 functions as a insulating layer for regulating heat flowing into the substrate 11 from the heating resistors 14.

Note that, the cavity portion 19 can have any size in a plan view. The cavity portion 19 may be larger than the heat generating portion like this embodiment or may be smaller than the heat generating portion, as long as the size thereof is close to the size of the heat generating portion.

The adhesive layer 12 bonds the one surface of the substrate 11 to the another surface of the heat storage layer 13, and absorbs a thermal expansion difference (thermal extension difference) that occurs between the substrate 11 and the heat storage layer 13.

As a material for the adhesive layer 12, there is used a high heat-resistance material capable of withstanding a temperature of the heating resistors 14 that rises up to approximately from 200 to 300 degrees centigrade, for example, an organic resin material such as a polyimide resin, a polyamideimide resin, an epoxy resin, an acrylic resin, a silicone resin, or a fluororesin.

Next, description is made, with reference to FIGS. 4 to 10, of a manufacturing method for the thermal head 4 according to this embodiment.

First, as illustrated in FIG. 4, the concave portion 20 is formed so as to provide the cavity portion 19 at the region opposed to a heat generating portion of each of the plurality of heating resistors 14 of the surface of the substrate 11 having a constant thickness (approximately 300 μm to 1 mm). Concerning material of the substrate 11, for example, a glass substrate, a monocrystal silicon substrate, or a ceramic substrate (alumina substrate) is used. The glass substrate is made of soda glass having the thermal expansion coefficient (thermal expansion ratio) of 8.6×10^{-6} per degree centigrade, Pyrex glass having the thermal expansion coefficient of 3.2×10^{-6} per degree centigrade, no alkali glass having the thermal expansion coefficient of 3.8×10^{-6} per degree centigrade, or the like. The monocrystal silicon substrate has the thermal expansion coefficient of 3.3×10^{-6} per degree centigrade. The ceramic substrate has the thermal expansion coefficient of 7.2×10^{-6} per degree centigrade.

The concave portion 20 is formed on the surface of the substrate 11 by sandblasting, dry etching, wet etching, laser processing, or the like.

Note that, in the case where the substrate 11 is processed by sandblasting, the surface of the substrate 11 is covered with a photoresist material, and the photoresist material is exposed to light using a photo mask having a predetermined pattern, to thereby solidify a portion other than a region in which the concave portions 20 are to be formed. Then, the surface of the substrate 11 is washed, and the photoresist material which is not solidified is removed, to thereby obtain an etching mask having etching windows formed in the region in which the concave portions 20 are to be formed. The surface of the substrate 11 is subjected to sandblasting in this state, and thus the concave portion 20 having a predetermined depth is obtained.

In the case where processing is performed through etching, the etching mask having the etching windows formed in the region in which the concave portions 20 are to be formed is formed on the surface of the substrate 11 in the same manner, and the surface of the substrate 11 is subjected to etching in this state, whereby the concave portion 20 having the predetermined depth is obtained. In the etching process, for example, wet etching is performed using an etching liquid such as a tetramethylammonium hydroxide solution, a KOH solution, or a mixed liquid of fluorinated acid and nitric acid in the case of the single-crystal silicon, and wet etching is performed using a fluorinated acid etching liquid or the like in the case of the glass substrate. In addition, dry etching such as reactive ion etching (RIE) or plasma etching is employed.

Next, as illustrated in FIG. 5, the paste-like, liquid-like, film-like, or sheet-like adhesive layer 12 is laminated (formed) on the entire of the another surface of the heat storage layer 13 having a constant thickness (approximately 2 μm to 20 μm).

Next, as illustrated in FIG. 6, the adhesive layer 12 and the heat storage layer 13 obtained as illustrated in FIG. 5 are overlaid on the surface of the substrate 11 from which an etching mask is removed completely, and hence the another surface of the adhesive layer 12 (surface opposite to the surface opposed to the heat storage layer 13) contacts with the substrate 11. Then, a predetermined temperature and load are applied uniformly for a certain time period, and hence the substrate 11 and the heat storage layer 13 are bonded (glued) to each other. Concerning material of the heat storage layer 13, for example, a glass substrate is used, which is made of soda glass having the thermal expansion coefficient of 8.6×10^{-6} per degree centigrade, Pyrex glass having the thermal expansion coefficient of 3.2×10^{-6} per degree centigrade, no alkali glass having the thermal expansion coefficient of 3.8×10^{-6} per degree centigrade, or the like.

Here, the heat storage layer 13 made of a thin glass substrate having a thickness of approximately 2 μm to 20 μm is difficult to manufacture or handle, and is expensive. Therefore, instead of bonding the above-mentioned heat storage layer 13 made of a thin glass substrate directly to the substrate 11, the heat storage layer 13 made of glass substrate having a thickness that is easy to manufacture or handle may be bonded to the substrate 11 and afterward the heat storage layer 13 may be processed to have a desired thickness by etching or polishing. In this case, the very thin heat storage layer 13 can be formed uniformly and inexpensively on the one surface of the substrate 11 with ease.

As the etching of the heat storage layer 13 made of a glass substrate, various types of etchings used for forming the concave portion 20 can be used. In addition, the heat storage layer 13 made of a glass substrate can be polished by chemical mechanical polishing (CMP) or the like, which is used for high accuracy polishing of a semiconductor wafer and the like.

Then, on the heat storage layer 13 formed as described above, the heating resistor layer 16 (see FIG. 7), individual electrodes 17 (see FIG. 8), a common electrode 18 (see FIG. 9), and the protective film 15 (see FIG. 10) are sequentially formed. Note that, the order of forming the heating resistor layer 16, the individual electrodes 17, and the common electrode 18 is arbitrary.

The heating resistor layer 16, the individual electrodes 17, the common electrode 18, and the protective film 15 can be manufactured by using a manufacturing method for those members of a conventional thermal head. Specifically, a thin film formation method such as sputtering, chemical vapor deposition (CVD), or vapor deposition is used to form a thin film made of a Ta-based or silicide-based heating resistor material on the insulating film. Then, the thin film made of the heating resistor material is molded by lift-off, etching, or the like, whereby the heating resistor having a desired shape is formed.

Similarly, the film formation with use of an electrode material such as Al, Al—Si, Au, Ag, Cu, and Pt is performed on the heat storage layer 13 by using sputtering, vapor deposition, or the like. Then, the film thus obtained is formed by lift-off or etching, or the electrode material is screen-printed and is burned thereafter, to thereby form the individual electrodes 17 and the common electrode 18 which have the desired shapes.

After the above-mentioned formation of the heating resistor layer 16, the individual electrodes 17, and the common electrode 18, the film formation with use of a protective film material such as SiO₂, Ta₂O₅, SiAlON, Si₃N₄, or diamond-like carbon is performed on the heat storage layer 13 by sputtering, ion plating, CVD, or the like, whereby the protective film 15 is formed.

According to the thermal head 4 of this embodiment, the entire of the another surface of the heat storage layer 13 is covered with the adhesive layer 12 made of a resin, and hence the adhesive layer 12 reinforces the heat storage layer 13 (mechanical strength of the heat storage layer 13 is increased (improved)). Therefore, the thickness of the heat storage layer 13 can be reduced (to be 20 μm or smaller), and hence the time period for storing sufficient heat in the heat storage layer 13 can be shortened. Thus, the defective condition that the print density is low when the printing is started can be eliminated.

In addition, an amount of heat input into the heat storage layer 13 when the printing is started can be reduced by decreasing the thickness of the heat storage layer 13. Therefore, a thermal load applied to the entire thermal head 4 can be reduced, and hence durability and reliability can be improved.

Further, the thermal expansion difference that occurs between the substrate 11 and the heat storage layer 13 because of the temperature of the heating resistor 14 that rises up to approximately 200 to 300 degrees centigrade when the thermal head 4 is energized is absorbed by elastic deformation of the adhesive layer 12 made of an elastic material. Therefore, a warpage or a distortion of the thermal head 4 is eliminated (or reduced) when the thermal head 4 is energized, and hence the print quality can be maintained to be always in an optimal condition.

Still further, even if a monocrystal silicon substrate is adopted as a material of the substrate 11, soda glass that is inexpensive and has good workability can be adopted as a material of the heat storage layer 13. Therefore, manufacturing cost can be reduced and manufacturing steps can be simplified.

Still further, beneath the region covered with a heat generating portion of each of the plurality of heating resistors 14 (region opposed to the heat generating portion), there is

formed the cavity portion 19 having a sufficient height (depth) for improving the heat generating efficiency, that is, a heat insulating layer for restricting heat flowing into the substrate 11 from the heat storage layer 13. Therefore, the heat generating efficiency can be improved.

Further, according to the thermal printer 1 provided with the thermal head 4 according to this embodiment, because the thermal head 4 having high heat generating efficiency is provided, it is possible to perform printing onto the thermal recording paper 5 with small electric power. Therefore, it is possible to lengthen a duration time of a battery.

On the other hand, according to the manufacturing method for the thermal head 4 according to this embodiment, the entire of the another surface of the heat storage layer 13 is covered with the adhesive layer 12 made of a resin, so as to handle the heat storage layer 13 reinforced by the adhesive layer 12 (having increased (improved) mechanical strength). Therefore, manufacturing cost can be reduced and manufacturing steps can be simplified.

In addition, even if a monocrystal silicon substrate is adopted as a material of the substrate 11, soda glass that is inexpensive and has good workability can be adopted as a material of the heat storage layer 13. Therefore, manufacturing cost can be reduced and manufacturing steps can be simplified.

Note that, the paste-like or liquid-like adhesive layer 12 can be laminated on the entire of the another surface of the heat storage layer 13 by adopting methods including roll coating, printing, dipping, spin coating, spraying, and brush painting.

In addition, the film-like or sheet-like adhesive layer 12 can be laminated on the entire of the another surface of the heat storage layer 13 by adopting methods including pressing, bonding, and laminating.

A second embodiment of the thermal head according to the present invention is described with reference to FIG. 11. FIG. 11 is a process diagram for illustrating a manufacturing method for the thermal head according to this embodiment.

The thermal head according to this embodiment is different from that of the first embodiment described above in that the manufacturing steps of the former includes the step illustrated in FIG. 11, i.e., the step of laminating (forming) the film-like or sheet-like adhesive layer 12 on the surface of the substrate 11 from which the etching mask is removed completely, instead of the step (see FIG. 5) of laminating (forming) the paste-like, liquid-like, film-like, or sheet-like adhesive layer 12 on the entire of the another surface of the heat storage layer 13.

Other components are the same as those of the first embodiment described above, so description of the components is omitted here.

Note that, after the film-like or sheet-like adhesive layer 12 is laminated on the surface of the substrate 11, the heat storage layer 13 having a constant thickness (approximately 2 μm to 20 μm) is overlaid on the one surface (upper surface in FIG. 11) of the film-like or sheet-like adhesive layer 12, and a predetermined temperature and load are applied uniformly for a certain time period, and hence the substrate 11 and the heat storage layer 13 are bonded (glued) to each other (see FIG. 6). The actions and effects of the thermal head according to this embodiment and the thermal printer provided with the thermal head according to this embodiment are the same as those of the first embodiment, so description thereof is omitted here.

On the other hand, according to the manufacturing method for the thermal head according to this embodiment, the step of reversing (upside down) the heat storage layer 13 with the adhesive layer 12 laminated on the entire of the one surface is

11

eliminated. Therefore, manufacturing steps can be simplified and manufacturing cost can be reduced.

In addition, even if a monocrystal silicon substrate is adopted as a material of the substrate 11, soda glass that is inexpensive and has good workability can be adopted as a material of the heat storage layer 13. Therefore, manufacturing cost can be reduced and manufacturing steps can be simplified.

A third embodiment of a thermal head according to the present invention is described with reference to FIG. 12. FIG. 12 is a cross sectional view of the thermal head according to this embodiment, which is similar to FIG. 3.

As illustrated in FIG. 12, the thermal head 31 according to this embodiment is different from the thermal head of the first embodiment described above in that the former includes an adhesive layer 32 instead of the adhesive layer 12.

Other components are the same as those of the first embodiment described above, so description of the components is omitted here.

The manufacturing steps for the thermal head 31 according to this embodiment include the step illustrated in FIG. 13, i.e., the step of patterning the paste-like, liquid-like, film-like, or sheet-like adhesive layer 12 (see FIG. 5) laminated (formed) on the entire of the another surface of the heat storage layer 13 by laser, machining, photolithography or the like.

Note that, after the adhesive layer 32 is patterned and laminated on the another surface of the heat storage layer 13, the heat storage layer 13 and the adhesive layer 32 obtained as illustrated in FIG. 13 are overlaid on the surface of the substrate 11 from which the etching mask is removed completely so that the another surface of the adhesive layer 32 (surface opposite to the surface opposed to the heat storage layer 13) contacts with the substrate 11. Then, a predetermined temperature and load are applied uniformly for a certain time period, and hence the substrate 11 and the heat storage layer 13 are bonded (glued) to each other.

According to the thermal head 31 of this embodiment, a part of the another surface of the heat storage layer 13 positioned beneath the region covered with the heat generating portion of each of the plurality of the heating resistors 14 (region opposed to the heat generating portion) is exposed to the cavity portion 19. Therefore, heat dissipation via the adhesive layer 32 can be suppressed so that the heat generating efficiency can be further improved.

Note that, on the one surface of the substrate 11 on which the concave portion 20 is formed, the adhesive layer 32 is laminated (formed) on the entire region except for the region in which the concave portion 20 is formed.

In addition, the coefficient of thermal conductivity of glass is 0.9 W/mK, the coefficient of thermal conductivity of air is 0.02 W/mK, and the coefficient of thermal conductivity of an epoxy resin is 0.21 W/mK.

Other actions and effects are the same as those of the embodiments described above, so description thereof is omitted here.

The actions and effects of the thermal printer provided with the thermal head according to this embodiment and the manufacturing method for the thermal head according to this embodiment are the same as those of the embodiments described above, so description thereof is omitted here.

Note that, when the patterned adhesive layer 32 is laminated on the another surface of the heat storage layer 13, the film-like or sheet-like adhesive layer 12 may be patterned in advance as illustrated in FIG. 14 so as to be laminated on the another surface of the heat storage layer 13 having a constant thickness (approximately 2 μ m to 20 μ m). Alternatively, the paste-like or liquid-like adhesive layer may be printed in a

12

predetermined pattern to be laminated on the another surface of the heat storage layer 13 having a constant thickness (approximately 2 μ m to 20 μ m) by screen printing, intaglio printing, relief printing, or the like.

5 In addition, (similarly to FIG. 11), the film-like or sheet-like adhesive layer 32 patterned in advance as illustrated in FIG. 14 may be laminated (formed) on the surface of the substrate 11 from which the etching mask is removed completely, and afterward the heat storage layer 13 having a 10 constant thickness (approximately 2 μ m to 20 μ m) may be overlaid so that they are bonded (glued) to each other.

A fourth embodiment of a thermal head according to the present invention is described with reference to FIG. 15. FIG. 15 is a cross sectional view of the thermal head according to this embodiment, which is similar to FIG. 3.

As illustrated in FIG. 15, the thermal head 41 according to this embodiment is different from the thermal heads of the first and second embodiments described above in that the former includes an adhesive layer 42 instead of the adhesive layer 12.

Other components are the same as those of the first and second embodiments described above, so description of the components is omitted here.

The manufacturing steps for the thermal head according to 25 this embodiment include the step of patterning the paste-like, liquid-like, film-like, or sheet-like adhesive layer 12 (see FIG. 5) laminated (formed) on the entire of the another surface of the heat storage layer 13 by laser, machining, photolithography, or the like.

30 Note that, after the adhesive layer 42 is patterned and laminated on the another surface of the heat storage layer 13, the adhesive layer 42 and the heat storage layer 13 are overlaid on the surface of the substrate 11 from which the etching mask is removed completely so that the another surface of the adhesive layer 42 (surface opposite to the surface opposed to the heat storage layer 13) contacts with the substrate 11. Then, a predetermined temperature and load are applied uniformly for a certain time period, and hence the substrate 11 and the heat storage layer 13 are bonded (glued) to each other.

40 According to the thermal head 41 of this embodiment, a part of the another surface of the heat storage layer 13 is exposed to the cavity portion 19, and a region without the adhesive layer between the another surface of the heat storage layer 13 and the one surface of the substrate 11 (region in which the heat storage layer 13 and the substrate 11 are not bonded to each other via the adhesive layer 42) is formed. Therefore, heat dissipation via the adhesive layer 42 can be suppressed so that the heat generating efficiency can be further improved.

45 Note that, the coefficient of thermal conductivity of glass is 0.9 W/mK, the coefficient of thermal conductivity of air is 0.02 W/mK, and the coefficient of thermal conductivity of an epoxy resin is 0.21 W/mK.

50 Other actions and effects are the same as those of the 55 embodiments described above, so description thereof is omitted here.

The actions and effects of the thermal printer provided with the thermal head according to this embodiment and the manufacturing method for the thermal head according to this 60 embodiment are the same as those of the embodiments described above, so description thereof is omitted here.

Note that, when the patterned adhesive layer 42 is laminated on the another surface of the heat storage layer 13, the film-like or sheet-like adhesive layer 12 may be patterned in advance so as to be laminated on the another surface of the heat storage layer 13 having a constant thickness (approximately 2 μ m to 20 μ m). Alternatively, the paste-like or liquid-

13

like adhesive layer may be printed in a predetermined pattern to be laminated on the another surface of the heat storage layer 13 having a constant thickness (approximately 2 μm to 20 μm) by screen printing, intaglio printing, relief printing or the like.

In addition, (similarly to FIG. 11), the film-like or sheet-like adhesive layer 42 patterned in advance may be laminated (formed) on the surface of the substrate 11 from which the etching mask is removed completely, and afterward the heat storage layer 13 having a constant thickness (approximately 2 μm to 20 μm) may be overlaid so that they are bonded (glued) to each other.

A fifth embodiment of a thermal head according to the present invention is described with reference to FIG. 16. FIG. 16 is a cross sectional view of the thermal head according to this embodiment, which is similar to FIG. 3.

As illustrated in FIG. 16, the thermal head 51 according to this embodiment is different from that of the first embodiment described above in that the former includes an adhesive layer 52 instead of the adhesive layer 12.

Other components are the same as those of the first embodiment described above, so description of the components is omitted here.

The manufacturing steps for the thermal head 51 according to this embodiment include the step of patterning the paste-like, liquid-like, film-like, or sheet-like adhesive layer 12 (see FIG. 5) laminated (formed) on the entire of the another surface of the heat storage layer 13 by laser, machining, photolithography, or the like.

Note that, after the patterned adhesive layer 52 is laminated on the another surface of the heat storage layer 13, the adhesive layer 52 and the heat storage layer 13 are overlaid on the surface of the substrate 11 from which the etching mask is removed completely so that the another surface of the adhesive layer 52 (surface opposite to the surface opposed to the heat storage layer 13) contacts with the substrate 11. Then, a predetermined temperature and load are applied uniformly for a certain time period, and hence the substrate 11 and the heat storage layer 13 are bonded (glued) to each other.

According to the thermal head 51 of this embodiment, a part of the another surface of the heat storage layer 13 positioned beneath the region covered with the heat generating portion of each of the plurality of the heating resistors 14 (region opposed to the heat generating portion) is exposed to the cavity portion 19. Therefore, heat dissipation via the adhesive layer 52 can be suppressed so that the heat generating efficiency can be further improved.

Note that, on the one surface of the substrate 11 on which the concave portion 20 is formed, the adhesive layer 52 is laminated (formed) on the entire region except for the region in which the concave portion 20 is formed.

In addition, the coefficient of thermal conductivity of glass is 0.9 W/mK, the coefficient of thermal conductivity of air is 0.02 W/mK, and the coefficient of thermal conductivity of an epoxy resin is 0.21 W/mK.

Other actions and effects are the same as those of the embodiments described above, so description thereof is omitted here.

The actions and effects of the thermal printer provided with the thermal head according to this embodiment and the manufacturing method for the thermal head according to this embodiment are the same as those of the embodiments described above, so description thereof is omitted here.

Note that, when the patterned adhesive layer 52 is laminated on the another surface of the heat storage layer 13, the film-like or sheet-like adhesive layer 12 may be patterned in advance so as to be laminated on the another surface of the

14

heat storage layer 13 having a constant thickness (approximately 2 μm to 20 μm). Alternatively, the paste-like or liquid-like adhesive layer may be printed in a predetermined pattern to be laminated on the another surface of the heat storage layer 13 having a constant thickness (approximately 2 μm to 20 μm) by screen printing, intaglio printing, relief printing, or the like.

In addition, (similarly to FIG. 11), the film-like or sheet-like adhesive layer 52 patterned in advance may be laminated (formed) on the surface of the substrate 11 from which the etching mask is removed completely, and afterward the heat storage layer 13 having a constant thickness (approximately 2 μm to 20 μm) may be overlaid so that they are bonded (glued) to each other.

A sixth embodiment of a thermal head according to the present invention is described with reference to FIG. 17. FIG. 17 is a cross sectional view of the thermal head according to this embodiment, which is similar to FIG. 3.

As illustrated in FIG. 17, the thermal head 61 according to this embodiment is different from that of the first embodiment described above in that the former includes an adhesive layer 62 instead of the adhesive layer 12.

Other components are the same as the first embodiment described above, so description of the components is omitted here.

The manufacturing steps for the thermal head 61 according to this embodiment include the step of patterning the paste-like, liquid-like, film-like, or sheet-like adhesive layer 12 (see FIG. 5) laminated (formed) on the entire of the another surface of the heat storage layer 13 by laser, machining, photolithography, or the like.

Note that, after the patterned adhesive layer 62 is laminated on the another surface of the heat storage layer 13, the adhesive layer 62 and the heat storage layer 13 are overlaid on the surface of the substrate 11 from which the etching mask is removed completely so that the another surface of the adhesive layer 62 (surface opposite to the surface opposed to the heat storage layer 13) contacts with the substrate 11. Then, a predetermined temperature and load are applied uniformly for a certain time period, and hence the substrate 11 and the heat storage layer 13 are bonded (glued) to each other.

According to the thermal head 61 of this embodiment, a part of the another surface of the heat storage layer 13 positioned beneath the region covered with the heat generating portion of each of the plurality of the heating resistors 14 (region opposed to the heat generating portion) is exposed to the cavity portion 19. Therefore, heat dissipation via the adhesive layer 62 can be suppressed so that the heat generating efficiency can be further improved.

Note that, on the one surface of the substrate 11 on which the concave portion 20 is formed, the adhesive layer 62 is laminated (formed) on the entire region except for the region in which the concave portion 20 is formed.

In addition, the coefficient of thermal conductivity of glass is 0.9 W/mK, the coefficient of thermal conductivity of air is 0.02 W/mK, and the coefficient of thermal conductivity of an epoxy resin is 0.21 W/mK.

Other actions and effects are the same as those of the embodiments described above, so description thereof is omitted here.

The actions and effects of the thermal printer provided with the thermal head according to this embodiment and the manufacturing method for the thermal head according to this embodiment are the same as those of the embodiments described above, so description thereof is omitted here.

Note that, when the patterned adhesive layer 62 is laminated on the another surface of the heat storage layer 13, the

15

film-like or sheet-like adhesive layer 12 may be patterned in advance so as to be laminated on the another surface of the heat storage layer 13 having a constant thickness (approximately 2 μm to 20 μm). Alternatively, the paste-like or liquid-like adhesive layer may be printed in a predetermined pattern to be laminated on the another surface of the heat storage layer 13 having a constant thickness (approximately 2 μm to 20 μm) by screen printing, intaglio printing, relief printing, or the like.

In addition, (similarly to FIG. 11), the film-like or sheet-like adhesive layer 62 patterned in advance may be laminated (formed) on the surface of the substrate 11 from which the etching mask is removed completely, and afterward the heat storage layer 13 having a constant thickness (approximately 2 μm to 20 μm) may be overlaid so that they are bonded (glued) to each other.

A seventh embodiment of a thermal head according to the present invention is described with reference to FIGS. 18 to 25.

FIG. 18 is a cross sectional view of the thermal head according to this embodiment, which is similar to FIG. 3, and FIGS. 19 to 25 are process diagrams for illustrating the manufacturing method for the thermal head according to this embodiment.

As illustrated in FIG. 18, the thermal head 71 according to this embodiment is different from that of the first embodiment described above in that the former includes an adhesive layer 72 instead of the adhesive layer 12 and that the former includes an substrate 73 instead of the substrate 11.

Other components are the same as the first embodiment described above, so description of the components is omitted here.

Next, with reference to FIGS. 19 to 25, the manufacturing method of the thermal head 71 according to this embodiment is described.

First, as illustrated in FIG. 19, the paste-like, liquid-like, film-like, or sheet-like adhesive layer 72 having a constant thickness (approximately 10 to 100 μm) is laminated (formed) on the entire of the another surface of the heat storage layer 13 having a constant thickness (approximately 2 μm to 20 μm).

Then, as illustrated in FIG. 20, the another surface of the adhesive layer 72 is processed to form a concave portion 75 that forms a cavity portion 74 and hence the cavity portion (hollow heat insulating layer) 74 is formed beneath the region covered with the heat generating portion of each of the plurality of the heating resistors 14 (region opposed to the heat generating portion). Note that, the adhesive layer 72 positioned beneath the region covered with the heat generating portion of each of the plurality of the heating resistors 14 (region opposed to the heat generating portion) (i.e., the adhesive layer 72 in the region where the concave portion 75 is formed) has a constant thickness (approximately 2 to 40 μm).

The cavity portion 74 is a space formed beneath the region covered with the heat generating portion of each of the plurality of the heating resistors 14 (region opposed to the heat generating portion), i.e., a space formed (enclosed) by the one surface of the substrate 73 (upper surface in FIG. 18), wall surfaces constituting the concave portion 75 (surfaces perpendicular to the one surface of the substrate 73 and the another surface of the heat storage layer 13) and the bottom surface (that is parallel to the one surface of the substrate 73 and the another surface of the heat storage layer 13). Further, the space layer in the cavity portion 74 has a function as a heat insulating layer for restricting heat flowing into the substrate 73 from the heating resistor 14. Note that, the cavity portion 74 can have any size in a plan view. The cavity portion 74 may

16

be larger than the heat generating portion like this embodiment or may be smaller than the heat generating portion, as long as the size thereof is close to the size of the heat generating portion.

Next, as illustrated in FIG. 21, the adhesive layer 72 and the heat storage layer 13 obtained as illustrated in FIG. 20 are overlaid on the surface of the substrate 73 having flat surfaces (one surface and another surface), and hence the another surface of the adhesive layer 72 (surface opposite to the surface opposed to the heat storage layer 13) contacts with the substrate 73. Then, a predetermined temperature and load are applied uniformly for a certain time period, and hence the substrate 73 and the heat storage layer 13 are bonded (glued) to each other.

Then, on the heat storage layer 13 formed as described above, a heating resistor layer 16 (see FIG. 22), individual electrodes 17 (see FIG. 23), a common electrode 18 (see FIG. 24), and a protective film 15 (see FIG. 25) are sequentially formed.

Actions and effects of a thermal head 81 according to this embodiment and a thermal printer provided with the thermal head 81 according to this embodiment, and actions and effects of a manufacturing method for the thermal head 81 according to this embodiment are the same as those of the embodiments described above, so description thereof is omitted here.

A eighth embodiment of a thermal head according to the present invention is described with reference to FIG. 26. FIG. 26 is a cross sectional view of the thermal head according to this embodiment, which is similar to FIG. 3.

As illustrated in FIG. 26, the thermal head 81 according to this embodiment is different from that of the seventh embodiment described above in that another surface of an adhesive layer 82 is processed to have a concave portion 84 having a trapezoidal cross section forming a cavity portion 83, and hence the cavity portion (hollow heat insulating layer) 83 is formed beneath the region covered with the heat generating portion of each of the plurality of the heating resistors 14 (region opposed to the heat generating portion).

Other components are the same as those of the seventh embodiment described above, so description of the components is omitted here.

Note that, the adhesive layer 82 positioned beneath the region covered with the heat generating portion of each of the plurality of the heating resistors 14 (region opposed to the heat generating portion) (i.e., the adhesive layer 82 in the region where the concave portion 84 is formed) has a thickness of approximately 2 to 40 μm at the thinnest part.

The cavity portion 83 is a space formed beneath the region covered with the heat generating portion of each of the plurality of the heating resistors 14 (region opposed to the heat generating portion), i.e., a space formed (enclosed) by the one surface of the substrate 73 (upper surface in FIG. 26), wall surfaces constituting the concave portion 84 (surfaces inclined with respect to the one surface of the substrate 73 and the another surface of the heat storage layer 13) and the bottom surface (that is parallel to the one surface of the substrate 73 and the another surface of the heat storage layer 13). Further, the space layer in the cavity portion 83 has a function as a heat insulating layer for restricting heat flowing into the substrate 73 from the heating resistor 14.

Note that, the cavity portion 83 can have any size in a plan view. The cavity portion 83 may be larger than the heat generating portion like this embodiment or may be smaller than the heat generating portion, as long as the size thereof is close to the size of the heat generating portion.

According to the thermal head 81 of this embodiment, the concave portion 84 is formed so that an open end of the concave portion 84 that contacts with the one surface of the substrate 73 is positioned outside with respect to the bottom surface constituting the concave portion 84, and that capacity (volume) of the cavity portion 83 is larger than capacity (volume) of the cavity portion in the embodiments described above. Therefore, heat dissipation via the adhesive layer 82 can be further suppressed so that the heat generating efficiency can be further improved.

Other actions and effects are the same as those of the embodiments described above, so description thereof is omitted here.

The actions and effects of the thermal printer provided with the thermal head according to this embodiment and the manufacturing method for the thermal head according to this embodiment are the same as those of the embodiments described above, so description thereof is omitted here.

A ninth embodiment of a thermal head according to the present invention is described with reference to FIG. 27. FIG. 27 is a cross sectional view of the thermal head according to this embodiment, which is similar to FIG. 3.

As illustrated in FIG. 27, the thermal head 91 according to this embodiment is different from the thermal head of the seventh embodiment described above in that the former includes an adhesive layer 92 instead of the adhesive layer 72.

Other components are the same as those of the seventh embodiment described above, so description of the components is omitted here.

The manufacturing steps for the thermal head 91 according to this embodiment include the step illustrated in FIG. 28, i.e., the step of patterning the paste-like, liquid-like, film-like, or sheet-like adhesive layer 72 (see FIG. 19) laminated (formed) on the entire of the another surface of the heat storage layer 13 by laser, machining, photolithography, or the like.

Note that, after the adhesive layer 92 is patterned and laminated on the another surface of the heat storage layer 13, the adhesive layer 92 and the heat storage layer 13 obtained as illustrated in FIG. 28 are overlaid on the surface of the substrate 73 so that the another surface of the adhesive layer 92 (surface opposite to the surface opposed to the heat storage layer 13) contacts with the substrate 73. Then, a predetermined temperature and load are applied uniformly for a certain time period, and hence the substrate 73 and the heat storage layer 13 are bonded (glued) to each other.

According to the thermal head 91 of this embodiment, a part of the another surface of the heat storage layer 13 positioned beneath the region covered with the heat generating portion of each of the plurality of the heating resistors 14 (region opposed to the heat generating portion) is exposed to the cavity portion 74. Therefore, heat dissipation via the adhesive layer 92 can be suppressed so that the heat generating efficiency can be further improved.

Other actions and effects are the same as those of the embodiments described above, so description thereof is omitted here.

The actions and effects of the thermal printer provided with the thermal head according to this embodiment and the manufacturing method for the thermal head according to this embodiment are the same as those of the embodiments described above, so description thereof is omitted here.

Further, concerning the substrate 73 and the heat storage layer 13, as illustrated in FIG. 29, an adhesive layer 92a positioned beneath the region covered with the heat generating portion of each of the plurality of the heating resistors 14 (region opposed to the heat generating portion) may be laminated (formed) on the another surface of the heat storage layer

13. Then, as illustrated in FIG. 30, an adhesive layer 92b contacting with both the one surface of the substrate 73 and the another surface of the heat storage layer 13 may be laminated (formed) on the one surface of the substrate 73. Then, the another surface of the heat storage layer 13 may be overlaid on the one surface of the adhesive layer 92b so that they contact with each other, and a predetermined temperature and load may be applied uniformly for a certain time period, and hence the substrate 73 and the heat storage layer 13 are bonded (glued) to each other.

A tenth embodiment of a thermal head according to the present invention is described with reference to FIG. 31. FIG. 31 is a cross sectional view of the thermal head according to this embodiment, which is similar to FIG. 3.

As illustrated in FIG. 31, the thermal head 101 according to this embodiment is different from the thermal head of the ninth embodiment described above in that the former includes an adhesive layer 102 instead of the adhesive layer 92.

Other components are the same as those of the ninth embodiment described above, so description of the components is omitted here.

The manufacturing steps for the thermal head according to this embodiment include the step of laminating a patterned adhesive layer 102a on the another surface of the heat storage layer 13 as illustrated in FIG. 32, the step of laminating (forming) the adhesive layer 92b on the one surface of the substrate 73 as illustrated in FIG. 30, the adhesive layer 92b contacting with both the one surface of the substrate 73 and the another surface of the adhesive layer 102a except for the adhesive layer 102a positioned beneath the region covered with the heat generating portion of each of the plurality of the heating resistors 14 (region opposed to the heat generating portion), and the step of overlaying the adhesive layer 102a on the one surface of the adhesive layer 92b so that the another surface of the adhesive layer 102a except for the adhesive layer 102a positioned beneath the region covered with the heat generating portion of each of the plurality of the heating resistors 14 contacts with the same, and applying a predetermined temperature and load uniformly for a certain time period, and hence the substrate 73 and the heat storage layer 13 are bonded (glued) to each other.

According to the thermal head 101 of this embodiment, a part of the another surface of the heat storage layer 13 is exposed to the cavity portion 74, and a region without the adhesive layer between the another surface of the heat storage layer 13 and the one surface of the adhesive layer 92b (region in which the heat storage layer 13 and the substrate 73 are not bonded to each other via the adhesive layer 102) is formed. Therefore, heat dissipation via the adhesive layer 102 can be further suppressed so that the heat generating efficiency can be further improved.

Other actions and effects are the same as those of the embodiments described above, so description thereof is omitted here.

The actions and effects of the thermal printer provided with the thermal head according to this embodiment and the manufacturing method for the thermal head according to this embodiment are the same as those of the embodiments described above, so description thereof is omitted here.

FIGS. 33 to 40 illustrate concrete examples of patterning the adhesive layers 32, 42, 92a and 102a, which are plan views of the adhesive layers 32, 42, 92a and 102a viewed from the side of the heat storage layer 13 or the side of the substrate 11 or 73.

19

Note that, the thermal head of the present invention is not limited to the embodiments described above, which can be appropriately modified, changed and combined depending on necessities.

For instance, the same numbers of the cavity portions 19 are formed as the heating resistors 14 in the embodiments described above, but the present invention is not limited to this structure. The cavity portions 19 may be formed to be connected over the heating resistors 14 along the arrangement direction of the heating resistors 14, so as to constitute one cavity portion.

According to the thermal head having the cavity portions described above, neighboring cavity portions are communicated to each other, and a part of an outflow path for heat (heat quantity) generated in the heating resistor 14 to the inside of the substrate 11 is blocked. Therefore, flowing out of the heat (heat quantity) generated in the heating resistor 14 to the inside of the substrate 11 can be further suppressed, heat generating efficiency of the heating resistor 14 can be further improved, and electric power consumption can be further reduced.

In addition, the above embodiments describe the thermal head and the thermal printer 1 that directly develops color by heat, but the present invention is not limited to this structure. The present invention can also be applied to a heating resistance element other than the thermal head or to a printer device other than the thermal printer 1.

For instance, the present invention can be applied to a heating resistance element component such as a thermal type inkjet head for jetting ink by heat or a valve type inkjet head. In addition, the present invention can also be applied to other electronic components having a film heating resistance element component such as a thermal erase head having a substantially similar structure to that of the thermal head, a fixing heater for a printer, or the like that needs thermal fixing, or a thin film heating resistance element of a light guide type optical component, and hence similar effects can be obtained.

Further, the present invention can be applied to a printer such as a thermal transfer printer using a sublimation type or a melting type transfer ribbon, a rewritable thermal printer capable of developing color and discharging of a print medium, or a heat-sensitive adhesive activating label printer, the adhesive exhibiting thermal adhesiveness.

20

What is claimed is:

1. A thermal head comprising:
a supporting substrate;
a heat storage layer laminated on a surface of the supporting substrate via an adhesive layer made of an elastic material; and
a plurality of heating resistors arranged with spaces therbetween on the heat storage layer, wherein:
a cavity portion is formed at a region between the supporting substrate and the heat storage layer, the region being opposed to a heat generating portion of each of the plurality of heating resistors, wherein the cavity portion comprises a concave portion formed in a back surface of the adhesive layer and the supporting substrate that closes the concave portion; and
the elastic material constituting the adhesive layer is arranged in a bonded state with respect to at least a part of a surface of the heat storage layer opposed to the cavity portion.

2. A thermal head according to claim 1, wherein the cavity portion comprises a concave portion formed in the surface of the supporting substrate and the adhesive layer that closes an open end of the concave portion.

3. A thermal head according to claim 1, wherein a part of the back surface of the heat storage layer opposed to the surface of the supporting substrate exposed to the cavity portion is exposed to the cavity portion.

4. A thermal printer provided with the thermal head according to claim 1.

5. A manufacturing method for a thermal head, comprising:
laminating an adhesive layer made of an elastic material on a surface of a heat storage layer;
forming a concave portion in a back surface of the adhesive layer and a supporting substrate that doses the concave portion;
bonding the heat storage layer in a laminated state with respect to a surface of the supporting substrate via the adhesive layer; and
forming a plurality of heating resistors with spaces therbetween at a region corresponding to the surface of the heat storage layer, the region being opposed to the concave portion.
